UNITED STATES PATENT OFFICE.

GEORGE H. GOLDSMITH, OF GREENVILLE, SOUTH CAROLINA.

TENSION DEVICE.

1,260,662.

Specification of Letters Patent. Patented Mar. 26, 1918.

Application filed March 15, 1917. Serial No. 154,997.

To all whom it may concern:

Be it known that I, GEORGE H. GOLDSMITH, a citizen of the United States, residing at Greenville, in the county of Greenville and State of South Carolina, have invented certain new and useful Improvements in Tension Devices, of which the following is a specification.

My invention relates to tension devices adapted for use upon spoolers and other textile machines requiring a tension device.

The essential objects of my invention are to enable the application of the yarn or thread thereto automatically by the ballooning of the thread during the winding; to insure a uniformity and exactitude of stress or tension upon the yarn or thread; to render it possible, by substitution of various sized devices, to modify the tension; to prevent the accidental escape from the device of the thread coils; to prevent wear; to insure against accumulation of dirt; to definitely limit and determine the number of wraps of yarn around the core or post; and to attain these ends in an inexpensive device, and one adapted to facile attachment to any construction of machine.

To the above ends essentially my invention consists in such parts and in such combinations of parts as fall within the scope of the appended claims.

In the accompanying drawings which form a part of this application

Figure 1 is a front elevation of my device and portions of parts adjacent thereto including the upper end of a cop or bobbin and the lower portion of a spool, and

Figs. 2 and 3, show the device in side and plan elevations respectively.

Like reference characters indicate like parts throughout the views.

In the present instance, my device is shown in conjunction with portions of the spool stand 5, thread guide rod 6, clamp 7, cop or bobbin 8 and spool 9.

The tension device is preferably formed from a wire or rod by bending, so that the device is an integral whole of maximum strength and freedom of irregularities. It comprises a vertical rod or core 10 whose upper end, in this instance, constitutes a horizontally disposed, angularly or radially turned stop finger 11.

At the inner end or bottom of the post 10, the material forms a resultant vertical loop 12 in the formation of a series of, in

this instance two, helices or coils 13 and 14, spaced from each other and from the rod or core 10 with which the coils are concentric. These coils constitute in effect a surrounding or exterior member 15, and the spaces between the coils define the number of turns of the yarn upon the rod 10. The outermost coil 14 terminates some distance below the finger or stop 11 and projects laterally beyond the exterior member forming a horizontal supporting arm 17 disposed at an angle to portion 11. The arm 17 is, in this instance, carried by the clamp 7 which engages the rod 6, and which carries the yarn guide, not shown, when it is desired to employ a guide. The arm 17 is consequently below and parallel with the rod 6, and the device is in the path of the twisting yarn 19 traveling from the bobbin 8 to the spool 9.

Either by ballooning or manually the yarn 19, assuming a position similar to that shown in broken lines, first contacts with the arm 17 and is guided by its curved end portion into and between the coils of the member 15. The yarn, however, as it initially enters the coil 14 from the rod 17, contacts with the stop finger or arm 11. The motion of the yarn and shape of the coils effect a wrapping or winding of the same around the rod between the coils; the number of turns being determined by the number of coil spaces. After the yarn has thus been wrapped upon the post, it is maintained against escape from the outer end of the rod by the member 11. The vertical loop 12, which constitutes a resultant shoulder, assists to control and retain the yarn from escaping from the bottom of the device, and without interfering with its vertical travel.

It will be observed therefore that the rotary movement of the yarn in ballooning brings it automatically into contact with my device and automatically wraps it thereon in an orderly manner with a predetermined number of turns which are maintained as the yarn continues to be drawn off from the bobbin.

It will be understood that the tension upon the yarn is determined by the frictional bearing thereof against the outer surface of the rod 10, and consequently by the number of turns of the yarn around the rod. Friction is further modified by the diameter of the rod.

I claim:—

1. A tension device comprising an interior member presenting an outer friction surface around which yarn may be wrapped with one or more turns and thereby retarded during the running of the yarn, and an exterior member loosely enveloping said interior member with a series of spaced coils adapted to define in a precise and determinate manner the number of turns of the yarn around said interior member upon the application of the yarn thereto. 45

5. A tension device comprising an interior member presenting an outer friction surface around which yarn may be wrapped with one or more turns and thereby retarded during the running of the yarn, a lateral stop upon said member for retaining the turns of yarn thereon and an exterior member extending around said interior member with a series of spaced coils and connecting with the inner end of said interior member, said exterior member having also an outwardly projecting arm for directing the yarn between its coils. 55
6. A tension device comprising an interior member consisting of a rod having a lateral stop upon its outer end, and an exterior member comprising a series of spaced coils surrounding said rod longitudinally thereof and connecting with the inner end thereof. 60
7. A tension device comprising an interior member consisting of a rod having a lateral stop upon its outer end, and an exterior member consisting of a series of longitudinally disposed spaced coils surrounding said rod and connecting with the inner end thereof, said exterior member being provided with an outwardly projecting arm upon the outermost coil. 75
8. A tension device comprising an interior member, a series of longitudinally disposed coils surrounding said member, a loop connecting the series of coils with one end of said member, and an arm continuous with one end coil of the series. 80
